Des. 233,914
Patented Dec. 10, 1974

233,914

DISPOSABLE CONTAINER FOR TOPICAL APPLICATION OF FLUID MEDICAMENTS

Claes Peter Lofman, Stockholm, Sweden, assignor to
Astra Lakemedel AB, Sodertalje, Sweden

Filed Nov. 8, 1971, Ser. No. 196,862

Term of patent 14 years

Int. Cl. D24—04

U.S. Cl. D83—1 N

The figure is a perspective view of a disposable container for topical application of fluid medicaments, showing my new design.

I claim:

The ornamental design for a disposable container for topical application of fluid medicaments, as shown.
